UNITED STATES PATENT OFFICE.

EDWARD ADOLPH JENSEN, OF MARINETTE, WISCONSIN.

DESIGN FOR A CHAFE-IRON.

SPECIFICATION forming part of Design No. 35,537, dated December 31, 1901.

Application filed October 26, 1901. Serial No. 80,156. Term of patent 14 years.

To all whom it may concern:

Be it known that I, EDWARD ADOLPH JENSEN, a citizen of the United States, residing at Marinette, in the county of Marinette and State of Wisconsin, have invented and produced a new and original Design for a Chafe-Iron, of which the following is a specification.

The invention relates to a new and original design for a chafe-iron, and has for its object o to provide a design of this character which will be both useful and ornamental.

The leading feature of the design resides in the design forming the subject-matter of the accompanying illustrations.

5 In the drawings, Figure 1 is a perspective view of a chafe-iron, showing my new and original design. Fig. 2 is a plan view of the same.

Referring to the drawings, 1 designates an o open frame or body composed of a straight portion 2 and arms 3 and 4, extending from the ends of the straight portion. The arm 4, which is shorter than the arm 3, extends from the straight portion 2 approximately at right angles thereto, and it tapers toward its outer end, where it is provided with a cylindrical

eye 5, arranged at an obtuse angle to the arm 4. The long arm 3 is tapered and continuously curved, and it presents an inner concave edge and an outer convex edge, and it is provided at its outer end with a cylindrical eye 5, extending longitudinally of the long arm and arranged parallel with the eye 5 of the short arm. The arms 3 and 4 converge and the cylindrical eyes project upward above 35 the plane of the body or frame 1. Extending across the space between the cylindrical eyes is a cylindrical roller. The cylindrical roller is smooth, and checkered bands 7 are arranged at the ends thereof adjacent to the 40 cylindrical eye.

Having thus described the invention, what is claimed as new is—

The design for a chafe-iron, as herein shown and described.

45 In testimony that I claim the foregoing as my own I have hereto affixed my signature in the presence of two witnesses.

EDWARD ADOLPH JENSEN.
